UNITED STATES PATENT OFFICE.

JOSEPH PLAUT, OF CINCINNATI, OHIO.

BERTH GUARD AND LADDER.

SPECIFICATION forming part of Letters Patent No. 700,233, dated May 20, 1902.

Application filed February 3, 1902. Serial No. 92,427. (No model.)

To all whom it may concern:

Be it known that I, JOSEPH PLAUT, a citizen of the United States, residing at Cincinnati, in the county of Hamilton and State of Ohio, have invented certain new and useful 5 Improvements in Béth Guards and Ladders, of which the following is a specification.

This invention pertains to berth guards and ladders for use in sleeping-cars, steamers, 10 and the like and relates to improvements upon the berth guard and ladder disclosed in Letters Patent of the United States No. 451,516, granted me May 5, 1891. These 15 improvements will be readily understood from the following description, taken in connection with the accompanying drawings, in which—

Figure 1 is a front elevation of three upper and three lower berths of an ordinary sleeping-car fitted with my improved ladder and guard, the device appearing at the left as a ladder, at the middle as a berth-guard, and at the right as hung on the ordinary curtain-rail. Fig. 2 is a perspective view of a portion of one of the ladder-rails, showing the preferred method of securing the ladder-rungs to the rails. Fig. 3 is a perspective view of an attaching-hook at the ends of the ladder-rails. Fig. 4 is a side elevation of a portion of one of the headboards or partitions between the berths, illustrating a form of attaching device to receive the hooks of the berth-guard. Fig. 5 is a perspective view of one of the straps employed to secure the ladder to the upper berth. Fig. 6 is a plan view of a portion of one of the ladder-rails, showing the attaching-band which serves to attach the berth guard and ladder to the curtain-rail. Fig. 7 is a cross-section on the line 40 $\alpha\alpha$ of Fig. 1, showing the manner of attaching the berth guard and ladder to the curtain-rail by means of the band taking over the curtain-rail from the interior of the ladder-rail and showing also the protecting-45 thimble to protect the leather ladder-rail from abrasive action of the band; and Fig. 8 is a cross-section of the ladder-rail, taken on the line $\gamma\gamma$ of Fig. 6, showing the attaching-band having its loop slipped within the tubing of 50 the ladder-rail for use as a berth guard or ladder and also showing the attaching-band in

dotted lines slipped outwardly and opened for receiving the curtain-rail.

A indicates the usual lower berths of a sleeping-car; B, the usual upper berths; C, 55 the usual curtain-rail over the berths; D, the usual headboards or vertical partitions between the berths; E, the hook-bars in mortises at the front edges of the headboards above the upper berth and forming attaching devices for the ladder; F, short straps, a pair on the front edge of each upper berth, one end of each strap being permanently secured to the berth, while the other end is arranged to button to the berth; G, a ladder, 65 shown at the left of Fig. 1 as arranged for use as a ladder proper in getting in and out of the upper berth and shown at the middle as arranged for use as a front guard for the upper berth to prevent the sleeper from being thrown out, and also shown at the right as secured to the curtain-rail for holding the ladder when out of use and making convenient disposition of the same where it is out of the way, while being convenient and handy 75 for immediate use in case it is required.

H represents the rails of the ladder, formed, preferably, of a tubing of leather I.

J represents the rungs of the ladder, formed, preferably, of twisted rope strands or wire, 80 these rungs passing through transverse holes in the ladder-rails, a button K at each side of each ladder-rung outside the ladder-rails securing the rungs in place, the strands of the rungs being run through the holes in the button, and the button thus preventing the rung from pulling out of the ladder-rail.

L is a hook secured in suitable manner at each end of the ladder-rail.

M is a band of resilient material having a 90 hook N at one end for taking into a hole O at its other end for forming a ring, which takes through two openings P Q in the ladder-rail in such manner that the ring may be shoved almost entirely through the openings 95 into the inside of the ladder-rail for getting it out of the way when using the device as a ladder or berth-guard and may also be pulled almost entirely outside the ladder-rail, so that it may be attached to the curtain-rail, but still remaining attached to the ladder-rail by that part R of the ladder-rail which is be-

tween the openings. The openings are also provided with metal thimbles S for protecting the leather of the ladder-rail from wear when the bands are slipped in and out, the 5 thimbles taking snugly against the sides of the bands for holding the same in or out, as desired. There is one of these bands near each end of the ladder-rail. These loops of the bands are normally slipped inwardly into 10 the hollow ladder-rail when the ladder is used as a ladder or a berth-guard; but when it is desired to hang up the ladder the bands are slipped outwardly and the hooks in the bands are disengaged from their holes. The bands 15 then open and are placed about the curtain-rails, when the hooks are again caught into the holes and the ladder is secured in place on the curtain-rail, conveniently ready for immediate use in case of requirement and out 20 of the way.

When the ladder is in the position shown in the left of Fig. 1, it is held to the upper berth by the straps F, the lower end of the ladder hanging freely down below the lower 25 berth, but not necessarily attached thereto. In this condition the ladder can be used for getting into and out of the upper berth. When the ladder is to be used as a berth-guard, its hook ends are engaged with the 30 attaching devices on the headboards, as will be readily understood from the middle portion of Fig. 1, and when the ladder is not in use as a ladder or berth-guard it is attached to the curtain-rail, as shown at the right-hand 35 portion of Fig. 1, conveniently ready for immediate use.

I claim as my invention—

1. In a berth guard and ladder, the combination substantially as set forth, of an upper 40 berth, vertical partitions at the head and foot of the berth, provided with attaching devices, a curtain-rail above the upper berth, a ladder

provided with hooks at its ends to engage said attaching devices when the ladder is disposed horizontally, fastenings at the front edge of 45 the berth to engage the ladder when disposed vertically, a resilient band near each end of the ladder taking about the curtain-rail when the ladder is disposed above the upper berth, rails for the ladder, openings in a rail for 50 each band, with a connection R of the rail between the openings supporting the ladder from the band, a recess in the rail for each band permitting the loops of the bands to be slipped within the rail when the ladder is so 55 disposed horizontally at the upper berth or vertically as stated, and also arranged for having the bands slipped outwardly about the curtain-rail for supporting the ladder above the upper berth, substantially as de- 60 scribed.

2. In a berth guard and ladder, the combination, substantially as set forth, of an upper berth, a curtain-rail above the same, the hollow leather ladder-rails H, the holes P, Q, 65 and connecting-piece R near each end of the ladder-rail, the thimbles S taking into the holes and protecting the leather, and the resilient bands M M taking about the curtain-rail and connecting-piece R and into the hollow rails through said holes P, Q, each band 70 having a hook N and a hole O, constructed and arranged for slipping the loops of the bands within the hollow rail and for opening the band and slipping the same about the 75 curtain-rail above the upper berth and thereby fastening the ladder thereto.

In testimony whereof I have signed my name hereto in the presence of two subscribing witnesses.

JOSEPH PLAUT.
